UNITED STATES PATENT OFFICE.

CARL MÜLLER, OF CHICAGO, ILLINOIS, ASSIGNOR TO MARDER LUSE & CO.,
OF SAME PLACE.

DESIGN FOR A BORDER FOR PRINTING-TYPE.

SPECIFICATION forming part of Design No. 13,850, dated April 10, 1883.

Application filed January 30, 1883. Term of patent 14 years.

To all whom it may concern:

Be it known that I, CARL MÜLLER, a citizen of the United States, residing at Chicago, in the county of Cook and State of Illinois, have invented and produced a new and original Design for a Border for Printing-Type, which I call "Picturesque Combination Border No. 24," of which the following is a specification, reference being had therein to the accompanying printed specimens.

The new design consists of the combined ornamental and picturesque borders for printing-type, as fully shown in the accompanying printed specimens.

What I claim as new, and desire to secure by Letters Patent, is—

The new design for a border for printing-type, substantially as herein set forth, and as shown in the accompanying printed specimens.

In testimony whereof I affix my signature in presence of two witnesses.

Witnesses: CARL MÜLLER.
